UNITED STATES PATENT OFFICE.

CHARLES LYNCH, OF HAMMOND, INDIANA.

DUMPING MOTOR-TRUCK.

1,157,560.

Specification of Letters Patent. Patented Oct. 19, 1915.

Application filed August 26, 1912. Serial No. 716,976.

To all whom it may concern:

Be it known that I, CHARLES LYNCH, a citizen of the United States, residing at Hammond, in the county of Lake and State 5 of Indiana, have invented certain new and useful Improvements in Dumping Motor-Trucks, of which the following is a specification.

My present invention relates to motor 10 trucks of the dumping type, and has reference more particularly to that style or type of dumping trucks wherein the tilting body is hinged to and across the rear end of the motor truck frame, and discharges the load 15 from the rear.

The chief object of my present invention is to provide a simple, reliable, and highly efficient mechanism, preferably operated by the power of the motor of the truck, for tilting 20 the body by raising and lowering its forward end, and a mechanism which shall be self-locking in all positions.

My invention also includes a novel improvement in the truck body itself, adapting 25 the latter to be used either as an ordinary tilting body on the motor truck frame, or to be bodily raised from the truck frame by a suitable derrick or other hoisting apparatus and swung to and above the desired point of 30 discharge.

My invention, its mode of operation and its advantages will all be readily understood when considered in connection with the accompanying drawings, which illustrate 35 one practical form in which the invention may be embodied, and in which—

Figure 1 is a side elevational view of the complete truck, the tilted or dumping position of the body being indicated by dotted lines. Figs. 2 and 3 are longitudinal and transverse sections through the bottom of 40 the body. Fig. 4 is a front elevational view of the power-operated mechanism for tilting the body. Fig. 5 is a side elevational view 45 of the same. Fig. 6 is a top plan view of the same. Fig. 7 is a detail front elevation showing the shiftable eccentric bearing of the forward end of the transmission shaft. Fig. 8 is an enlarged cross section on the line 50 8—8 of Fig. 6.

Referring to the drawings, 10 designates as an entirety the motor truck frame, to and across the rear end of which is pivoted at 11 a body designated as an entirety by 12. 55 This body may be of the usual rectangular form having side, bottom and front end

walls, and open at its rear end. In the preferred form herein shown, the body comprises a suitably stiffened metal box-like structure having a hinged rear end closure 60 or tail-gate 13 and resting upon a skeleton bottom frame 14 (Figs. 2 and 3).

To prevent longitudinal or lateral displacement of the box-like superstructure from the skeleton sub-frame, while permitting the former to be lifted off the latter, I provide on the metal floor of the superstructure longitudinal ribs 15 that engage grooves or kerfs 16 in the cross timbers of the sub-frame, as shown in Fig. 3, and, at their ends, 70 abut against the end timbers of said sub-frame, as clearly shown in Fig. 2. The tail-gate 13 is pivoted to the sides of the body at 17, and has forwardly projecting arms 18, the forward ends of which are connected 75 by links 19 to the sides of the truck frame 10, as at 20, whereby the tilting of the body automatically opens the tail-gate for the discharge of the load, as clearly illustrated by dotted lines in Fig. 1.

Referring now to my improved mechanism for effecting the tilting of the body, 21 designates each of a pair of side uprights of the truck frame, in and between which is journaled a shaft 22, and an underlying second 85 shaft 23. Fast on the outer projecting ends of shaft 22 are a pair of depending arms 24, the lower ends of which are connected by thrust links 25 to the front portion of the body 12; the connection being preferably, in 90 the form of the invention herein illustrated, to the opposite ends of the sub-frame structure 14 of the body. Rigid with the arms 24 are a pair of segment racks 26, with which mesh pinions 27 keyed on the outer ends of 95 the shaft 23; and fast on the shaft 23, between the side uprights 21 is a worm-wheel 28.

Journalized in and across a horizontal frame 29 (Fig. 6), which forms a base support for the side uprights 21, is a transmission shaft 30. The forward end of this shaft has an eccentric bearing in a journal sleeve 31 in turn mounted in a bearing bracket 32 secured to the frame 29, as clearly shown in 105 detail view, Fig. 7. Fast on the journal sleeve 31 is a lever 33 that extends upwardly to within reach of the driver, as shown in Fig. 1. Fast on the transmission shaft 30 is a sprocket wheel 34 and a spur pinion 35. 110 The sprocket wheel 34 drives, through a chain 36, a large sprocket wheel 37 loose on

a countershaft 38; and the spur pinion 35 drives a spur gear 39 also loose on the countershaft 38. Splined on the counter-shaft 38 (Fig. 8) by a feather 40 is a double-ended clutch member 41, the two faces of which are adapted to alternately engage co-operating clutch members 42 and 43 fast with the sprocket wheel 37 and the spur gear 39, respectively; whereby either of the latter 10 may be placed in driving relation to the countershaft 38 by the actuation of a clutch lever 44 that extends up to within reach of the driver, as shown in Fig. 1. Fast on the countershaft 38 is a worm 45 that engages 15 and drives the worm-wheel 28 on the shaft 23.

On the forward end of the transmission shaft 30 is a friction wheel 46 that is adapted to be thrown into and out of driven relation to the fly wheel 47 of the engine by suitable shifting of the lever 33.

It is evident that the chain and sprocket and spur gear transmissions between the shafts 30 and 38 serve, when coupled to the latter shaft, to drive the same in opposite directions. Hence, when the driver desires to 25 tilt the body for the dumping of the load, he first throws the friction wheel 46 into engagement with the engine fly wheel 47 by means of the lever 33, and he then, by means 30 of the clutch lever 44, shifts the clutch 41 into engagement with either the sprocket wheel 37 or the spur gear 39, accordingly as one or the other imparts the proper rotation 35 to the worm 45 to effect an upwardly swinging movement of the lifting arms 24; the clutch being reversely shifted when it is desired to effect a lowering and leveling movement of the body.

40 It will be observed that the power-transmitting mechanism includes the worm 45 and the worm-gear 28 when operating in both directions; and it is well known that a worm-gear drive is self-locking in all positions, thus making it unnecessary to provide dogs, ratchets, or other detents, for holding the body in elevated position when dumping.

From the foregoing it will be seen that the power mechanism for effecting the 45 tilting of the body is simple and positive in action and under the complete control of the driver in his seat.

In the form of body herein shown, wherein the box-like superstructure rests upon a 50 bottom frame that is pivoted to the truck frame, and is removable from said bottom frame, I attach to the upper edges of this box-like superstructure and its tail-gate rings or eyes 48 and 49, to which hoisting

chains or cables from an overhead derrick 60 may be attached; it being necessary only, when dumping the load by means of a derrick, to disconnect the tail-gate operating links 19 from the arms 18.

While I have described the preferred embodiment of my invention, it will be manifest to those skilled in the art that the mechanism may be modified in detail to suit particular conditions and differing truck-frame structures without involving any departure 70 from the invention or sacrificing any of the advantages thereof.

I claim—

1. In a dumping motor truck, a truck frame, a tilting body pivoted in rear of its longitudinal center to and across the rear end of the truck frame, a shaft mounted in and between side uprights of the truck frame, a pair of arms on said shaft, thrust links connecting the free ends of said arms with the forward portion of said body, segment racks rigid with said arms, a second shaft carrying pinions meshing with said segment racks, and mechanism for turning said last-named shaft in both directions. 85

2. In a dumping motor truck, a truck frame, a tilting body pivoted in rear of its longitudinal center to and across the rear end of said truck frame, a shaft mounted in and between side uprights of the truck frame, a pair of arms on said shaft, thrust links connecting the free ends of said arms with the forward portion of said body, segment racks rigid with said arms, a second shaft carrying pinions meshing with said segment racks, and a worm-gear drive for said last-named shaft. 95

3. In a dumping motor-truck, the combination with the truck-frame, of a tilting body pivoted to and across the rear end 100 of said truck-frame, a shaft mounted in and between side-uprights of the truck-frame, a pair of arms on said shaft, thrust-links connecting the free ends of said arms with the forward portion of said body, segment-racks rigid with said arms, a second shaft carrying pinions meshing with said segment-racks, and power mechanism for turning said last-named shaft in both directions, said power mechanism including a 105 friction-wheel and means for shifting the latter into and out of driven engagement with the engine fly-wheel of the motor-truck. 110

CHARLES LYNCH.
